(57) **CLAIM**

The ornamental design for an automobile interior as shown and described.

DESCRIPTION

FIG. 1 is a top, front perspective view of an automobile interior showing my new design; FIG. 2 is a cross-sectional rear perspective view thereof, taken from line 2-2 in FIG. 1; FIG. 3 is a front, left side perspective view thereof; FIG. 4 is a front, right side perspective view thereof; FIG. 5 is a cross-sectional left side perspective view thereof, taken along line 5-5 in FIG. 2; FIG. 6 is a top, rear perspective view thereof; FIG. 7 is a cross-sectional perspective view thereof, taken along line 7-7 in FIG. 6; FIG. 8 is a rear, right side perspective view thereof; FIG. 9 is a rear, left side perspective view thereof; and, FIG. 10 is a top view thereof.

The broken lines showing cross-sectional indicators form no part of the claimed design.

The dash-dot-dot broken lines showing cross-sectional indicators form no part of the claimed design. The dash-dash broken lines depicting a boundary around de-emphasized elements illustrate portions of the automobile interior that form no part of the claimed design.

1 Claim, 9 Drawing Sheets
